UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed June 1, 1928. Serial No. 282,144.

This invention relates to power tools of the fluid pressure type. While it has particular adaptation to certain combination tools, such as yoke riveters and is herein disclosed in such relation, it also provides features of more general application.

In using a yoke riveter or other tool whether of a directly similar nature or not, it is frequently the case that the tool must be operated in a restricted space or adjacent obstructions which interfere with the positioning of the tool. This is particularly the case when the power connection or throttle handle is at an angle to the tool. For example, it is frequently desirable to drive rivets in both the right and left sides of the interior of a hollow object which may be of rectangular or other shape. If a yoke riveter is used it is necessary that the throttle handle be arranged for swinging movement or other adjustment in order to clear the vertical walls of the object. Any part, however, which swings upon another is apt to become loosened or disengaged and this is particularly the case when applied to a percussive tool by reason of the vibration which results from the operation of the tool.

One object of the invention is to provide an improved swinging or swivel joint for a fluid conduit. Another object is to prevent disengagement or loosening of the parts. Still another object is to maintain a tight seal at the joint. Other objects will be apparent from the detailed description which follows.

In order to illustrate the invention, one concrete embodiment thereof is shown in the accompanying drawings, in which:

Fig. 1 is an elevational view of a yoke riveter showing the outer hammer casing in section;

Fig. 2 is a fragmentary sectional view on an enlarged scale of a portion of the tool shown in Fig. 1 taken substantially on the line 2-2 of Fig. 3;

Fig. 3 is an elevational view of the parts shown in Fig. 2 at an angle of rotation of 90° to the right;

Fig. 4 is an elevational view of the swivel head looking into the open end of the same;

Fig. 5 is a rear end elevational view of the tool casing; and

Fig. 6 is a plan view of the locking ring.

The embodiment of the invention chosen for the purpose of illustration comprises a power tool having a hollow casing A within which is mounted for sliding movement a fluid pressure operated riveting hammer B, the casing having secured thereto, either integrally or otherwise, a yoke C. Since the power tool or riveting hammer B forms no part of the present invention, description thereof is omitted. A power conduit, in the present instance for fluid pressure, such as compressed air, extends to casing A to supply motor B with operating fluid. The conduit D may include a throttle handle E of any suitable or desired form. The connection of the fluid conduit to casing A so as to permit free swiveling movement while securing and maintaining a fluid tight joint as well as the manner of locking the parts against loosening comprise the present invention.

The connection to casing A includes a head 7 having screwthreaded engagement with casing A and a hollow swivel end 8 for conduit D which may be joined directly to the throttle handle E as shown. The swivel end consists of a right angle extension 8a arranged to have a telescoping fit with a bore 7a therefor in head 7. Extension 8a is further reduced and provided with screw threads as indicated at 8b thereby providing a shoulder 8c, which is engaged by a steel retaining washer 9 held in place by a nut 10. As shown in Figs. 1 and 2, nut 10 is chamfered, as indicated at 10a, and when the swivel end 8 is assembled upon head 7, reduced extension 8b is expanded into the chamfer 10a to rivet the parts together. An annular enlargement 8d on end 8 is arranged to form an engaging face for the outer end of head 7. Interposed between head 7 and enlargement 8d on the one hand and between the head and bearing washer 9 on the other are packing members or washers 11. These washers, as shown, are counter sunk in head 7, the outer one partly and the inner one entirely, so that distortion and displacement

of the same is effectively prevented. These washers are preferably of rigid, wear resisting, non-metallic material, which will provide and maintain a fluid tight seal around 5 swivel end 8. Fibre or a fibrous composition is very satisfactory as a material for washers 11. Bearing washer 10 is keyed to swivel end 8b in any suitable or desired manner as by a pin 12, Figs. 1 and 2, engaging a slot in 10 the washer whereby relative movement of steel washer 9 and nut 10 is prevented.

With the parts in the swivel connection held in assembled arrangement without an opportunity to become loosened, it is also 15 necessary to make the connection between head 7 and casing A such that the swiveling of conduit D on the head and the vibration incident to the operation of motor B will not cause loosening. The preferred locking arrangement 20 comprises a ring or annulus 13 integral with or integrally secured to casing A somewhat forwardly of its reduced and threaded rear end. In the present instance annulus 13 is threaded upon casing A and 25 then welded thereto as indicated at 13a. The rearward portion of annulus 13 is reduced in diameter to form an annular recess 13b and this reduced portion of the annulus has a number of saw slots 13c, Figs. 2, 3, 30 and 5. The forward portion of head 7 is similarly reduced to form an annular recess 7b and the reduced portion is saw-slotted as indicated at 7c, Figs. 2, 3, and 4. The saw slots in the reduced portions of annulus 13 35 and head 7 differ in number to provide a vernier adjustment, as for example an odd number of slots in annulus 13, such as eleven, and an even number of slots in head 7, such as twelve. When head 7 is screwed upon 40 casing A, it is set up as tightly as possible and turned until one of the slots 13c registers or aligns with one of the slots 7c, the large number of slots and their odd and even arrangement with a difference of one permitting a very close adjustment. A locking 45 member is then applied which has a projection extending into the two aligned slots. By preference the locking member is in the form of a spring ring or clip 14 of a size to 50 encircle the reduced portion 7a and 13b of head 7 and annulus 13 and to seat in the annular groove provided thereby. Ring 14 has one end inturned as indicated at 14a to form a transverse locking projection which 55 extends into the aligned slots. The opposite end of the ring is preferably thinned or tapered as indicated at 14b to prevent accidental catching and displacement of the locking ring when the tool is in use.

60 From the above it will be apparent that the present invention provides a swivel joint for a power connection which is particularly adapted for use with fluid pressure percussive tools in that all of the parts are securely locked against relative movement or loosen-

ing regardless of the constant movement of the swivel joint and of the vibration of the tool due to the improved locking arrangement in the swivel joint itself and in the connection of the swivel head to the tool casting, and that the structure of the swivel joint itself is such as to maintain a fluid-tight connection for an exceptionally long period.

While the invention has been herein disclosed in what is considered to be its preferred form, it is to be understood that the invention is not limited to the specific details thereof but covers all changes, modifications and adaptations within the scope of the appended claim.

I claim as my invention:

The combination with a power tool of a power conduit thereto, and means providing a swivel connection between said tool and said conduit comprising a head on said tool having a bore therethrough, a swivel end on said conduit having an extension of a size to pass through the bore in said head and formed rearwardly of said extension with an annular enlargement to engage said head, means in the outer end of said extension to prevent its withdrawal from said bore comprising a washer and a nut formed with a chamfer, means keying said washer to said extension, said extension being expanded into the chamfer of said nut, fibre washers countersunk in said head on opposite sides thereof and engaged by said washer and said enlargement.

Signed by me at Detroit, in the county of Wayne, and State of Michigan this 25 day of May, 1928.

EDWARD W. STEVENS.
